Primary Examiner — Leah MacChiarolo*Assistant Examiner* — Taylor O Mortorff(74) *Attorney, Agent, or Firm* — AEON Law, PLLC; Adam L. K. Philipp; Charlotte E. Holoubek(57) **CLAIM**

The ornamental design for a dust extraction device, as shown and described.

DESCRIPTION

FIG. 1 is a left back perspective view of a dust extraction device;

FIG. 2 is a right front perspective view of the dust extraction device in FIG. 1;

FIG. 3 is a left view thereof;

FIG. 4 is a right view thereof;

FIG. 5 is a back view thereof, in a first different scale than FIG. 1;

FIG. 6 is a front view thereof, in the first different scale than FIG. 1;

FIG. 7 is a top view thereof, in a second different scale than FIG. 1; and,

FIG. 8 is a bottom view thereof, in the second different scale than FIG. 1.

1 Claim, 8 Drawing Sheets(56)
